UNITED STATES PATENT OFFICE.

WALLACE L. COOK, OF CHICAGO, ILLINOIS, ASSIGNOR TO RELIABLE ELECTRIC CO., OF CHICAGO, ILLINOIS, A CORPORATION OF ILLINOIS.

PROTECTOR.

Application filed November 29, 1928. Serial No 151,422.

My invention relates to thermal protective devices adapted to be inserted in an electric circuit for breaking the circuit when an excessive amount of current passing 5 through a portion of the device heats the same above a predetermined temperature.

It is a purpose of my invention to provide a thermal protective device having electrodes held in electrical engagement by 10 heat responsive material with means for causing a wide separation of said electrodes upon heating said material above a predetermined temperature.

It is a further purpose of my invention 15 to provide means whereby the electrodes of the thermal protective device may be reset after separation upon softening the heat responsive means.

Another purpose of my invention is to 20 provide an enclosing casing for the thermal protective device and indicating means projecting outside said casing to indicate whether the protective device is in open or closed circuit position and to aid in resetting said device in closed position after it has opened the circuit.

Other objects and advantages will appear 25 as the description proceeds when taken in connection with the accompanying drawing. 30 However, I wish it to be understood that I do not intend to limit myself to the exact details shown and described but that I intend to avail myself of all such modifications as would occur to one skilled in this 35 art and would fall within the scope of the claim.

In the drawings,—

Fig. 1 is a sectional view taken longitudinally through my improved thermal protector; and

Fig. 2 is a section on the line 2—2 of Fig. 1.

Referring now in detail to the drawings, the numeral 3 represents an elongated tubular casing which has on opposite ends thereof the terminal members 4 and 5, made of any suitable metallic material, and which are held on the tube 3 by means of punched-in portions such as illustrated at 6 and 7. 45 The tube 3 is made of an insulating composition which is sufficiently soft to permit the portions 6 and 7 to enter thereinto and firmly hold the terminals in place. The terminal 5 is further provided with inwardly extending portions 8 and 9 which hold

the disk 10 against one end of the tube 3 for a purpose which will presently appear. The terminal 5 has soldered thereto a conductor member 11 which extends inwardly through an opening in the insulating disk 10 and is coiled around the member 12 inside the tube 3. This member 12 has the outer end thereof extending through the disk 10, as shown clearly in Fig. 1, and the end 14 of the conductor 11 is soldered to the end 15 of the member 12 by means of a comparatively hard solder which is capable of withstanding considerable heat. The portion of the conductor 11 that is coiled around the member 12 serves as a heat coil adapted 70 on the passage of current therethrough to heat the member 12 and soften the solder shown at 15 to permit release of the electrode 16 when the member 12 is heated. Thus it will be seen, by this arrangement, 75 that the solder at 14 and the solder at 15 are completely separated and cannot contaminate each other, as would be the case if the conductor 11 were connected to the member 12 inside the tube and in close proximity to the solder 15. The opening in the member 12 which accommodates the solder 15 and the electrode 16 should be sufficiently large to permit the use of a considerable amount of solder so as to avoid any danger 80 of binding between the electrodes 12 and 16 when the solder is softened under heat. The electrode 16 has a portion 17 consisting of a long rod which projects lengthwise through the tube 3 and out through the end 90 of the terminal 4. This rod 17 serves as an indicator to show whether or not the electrodes 12 and 16 are in contact with each other, and serves a further purpose 95 which will presently appear.

Secured to the electrode 16, as at 18, is a spring member 19 which surrounds the rod 17 and has its free end soldered to the terminal 4 at 20. This spring is adapted to be under tension when the electrodes 12 and 16 are in contact, so that upon undue heating of the electrode 12 due to a current flowing from terminal 5 through conductor 11, electrode 12, electrode 16, spring 19 and terminal 4, the spring will serve to pull the electrode 16 away from the electrode 12 and create a wide break between the two electrodes, thus breaking the circuit in which the protector is inserted and separating the electrodes far enough apart to prevent any 110

danger of a high voltage jumping the gap between them. The rod 17 is insulated from the terminal 4 by means of an insulating tube 21, which also extends downwardly inside the tube 3 to a point adjacent the end 18 of the spring 19. The purpose of this member 21 is to insulate the rod 17 and thus make the spring member 19 the only means connecting the electrode 16 with the terminal 4.

After the electrodes have been separated, due to the action of the spring 19 and the softening of the solder 15, the device may be reset by applying sufficient heat thereto 15. to soften the comparatively soft solder 15 and pushing the rod 17 inwardly so as to cause the electrode 16 to extend down into the electrode 12. The parts may be then held in this position until the solder cools 20 enough to hold the electrodes 12 and 16 together. In some cases it might happen that the spring 19 would break, and this would not interfere with the resetting of the device; but, as is clearly apparent, if the member 25 17 were not insulated from the terminal 4 the protector would be useless, since the spring would be out of commission and there would be no means for creating a gap by separating the members 12 and 16 when the solder was melted by the heat. In this way 30 it might happen that a protector would be reset and installed without any one becoming aware of the fact that it could not open the circuit because the spring was broken. 35 By use of the insulating tube 21, I make the spring 19 the only electrical connection between electrode 16 and terminal 4, so if the spring breaks, even though it is not visible from the outside, resetting of the two electrodes 12 and 16 will not complete the circuit 40 between terminals 4 and 5, and there

will be no danger of the tube being inserted in a circuit unless it can serve its purpose as a protector.

From the above description it will be seen 45 that I have provided a thermal protector wherein the solder heated by the heat coil to release the electrodes cannot be contaminated by the inferior solder used for securing the conductors, and one wherein a wide 50 separation of the electrodes is obtained, together with means for resetting and indicating the position of the electrodes without exposing any of the parts of the protector; and that, furthermore, I have provided means whereby the electrodes cannot 55 be reset to close the circuit if the spring for separating them happens to be broken.

Having thus described my invention, what I claim and desire to secure by Letters 60 Patent is:

A thermal protector of the character described comprising a pair of electrodes, heat responsive means for normally retaining said electrodes in electrical engagement and adapted upon undue increase in heat to permit separation of said electrodes, a spring normally under stress adapted to cause a wide separation of said electrodes upon softening of said heat responsive 65 means, means for again setting said electrodes into operative position upon re-softening of said heat responsive means, an enclosing shell housing said electrodes, heat responsive means and spring, and indicating 70 means projecting from said shell for indicating the relative position of said electrodes with respect to each other. 75

In witness whereof, I hereunto subscribe my name this 4th day of November, A. D., 80 1926.

WALLACE L. COOK.
